UNITED STATES PATENT OFFICE

106,939

DESIGN FOR AN AIRPLANE

Waldo D. Waterman, Santa Monica, Calif.

Application February 8, 1937, Serial No. 67,508

Term of patent 3½ years

To all whom it may concern:

Be it known that I, Waldo D. Waterman, a citizen of the United States, residing at Santa Monica, in the county of Los Angeles and State of California, have invented a new, original, and ornamental Design for an Airplane, of which the following is a specification, reference being had to the accompanying drawing, forming part thereof.

Figure 1 is a front elevation, Figure 2 a side elevation, Figure 3 a plan and Figure 4 a perspective view of the airplane as it would appear when in flight.

I claim:

The ornamental design for an airplane, as shown and described.

WALDO D. WATERMAN.
